UNITED STATES PATENT OFFICE.

WILLIAM GORDON, OF BOSTON, MASSACHUSETTS.

SOLE-EDGE-BURNISHING MACHINE.

SPECIFICATION forming part of Letters Patent No. 241,970, dated May 24, 1881.

Application filed April 4, 1881. (No model.)

To all whom it may concern:

Be it known that I, WILLIAM GORDON, of Boston, in the county of Suffolk and State of Massachusetts, have invented certain Improvements in Sole-Edge-Burnishing Machines, of which the following is a specification.

This invention relates to that class of sole-edge-burnishing machines in which a reciprocating burnishing-tool is employed.

10 The object of the invention is to provide improved means for laterally supporting or steadyng a boot or shoe when the same is held in position to present the toe portion of its sole to the burnishing-tool. The tool has a tendency to throw off or displace laterally the sole when its toe portion is being acted on, and means have to be provided to enable the operator to steady the sole and prevent its lateral displacement. The following devices have 15 been employed for this purpose: first, a hook adapted to be grasped by the finger of the operator; second, a rest arranged to support the bottom of the sole; third, a rest for the back of the operator's hand, the sole bearing against the front of the same; and, fourth, two rests arranged to support the edges of the sole laterally, said rests being rigid and immovable, as described hereinafter.

20 My invention consists in the combination, with a reciprocating burnishing-tool, of a pair of lateral rests adapted to bear with a yielding pressure against the opposite edges of the sole when the latter is held in position to present the toe thereof to the tool; said rests being 25 adapted to be moved into and out of their operative position, as I will now proceed to describe.

20 Of the accompanying drawings, forming part of this specification, Figure 1 represents a side elevation of a portion of an edge-setting machine embodying my invention. Fig. 2 represents a front elevation of the same. Fig. 3 represents a side view of a modification. Fig. 4 represents a perspective view of the rests detached from the machine.

45 In these figures the same letters refer to the same parts.

In the drawings, A represents the reciprocating tool of a sole-edge-burnishing machine, the same being of any suitable construction—for example, that shown in Letters Patent of

the United States No. 190,484, dated May 8, 1877.

B represents the pillar or support on which the reciprocating tool and its operating mechanism are located. The tool is reciprocated horizontally in a rectilinear path by mechanism such as is shown in the aforesaid patent, or by other suitable mechanism.

C represent the lateral rests which form the subject of my invention. These rests have the following characteristics, viz: first, when in operative position each rest is adapted to bear on opposite sides of a sole, close to the toe, when the sole is held vertically in presenting the toe thereof to the tool A; second, each rest bears against the sole with a yielding pressure, which is sufficiently forcible to materially aid the operator in keeping the sole in place laterally, and overcoming the tendency of the tool to displace or throw off the sole, at the same time the pressure being sufficiently yielding to enable the sole to be inclined laterally or edgewise while embraced by said rests, so that all parts of the toe portion can be presented to the tool, the rests yielding or separating to permit such inclination of the sole; third, the rests are adapted to be readily moved out of their operative position when other parts of the sole-edge than the toe portion are to be presented to the tool.

It is obvious that the construction whereby the above-named characteristics are imparted to the rests may be variously modified.

The construction shown in Figs. 1, 2, and 4 of the drawings is, perhaps, the best of which I am at present aware, and has been found satisfactory by practical tests. In the construction shown each rest is composed of an elastic plate or arm, 1, preferably of sheet-steel, pivoted at D to a rigid arm, E, which is rigidly attached to the pillar or support B by any suitable means. Said plates or arms 11 are formed with two elbows or angles, as shown, whereby the outer portions, 22, which constitute the rests proper, are extended outwardly and upwardly from the arms E. The outer portions, 22, are preferably formed with convex inner surfaces, to avoid presenting angles liable to deface the sole. The elasticity of the arms 11 is sufficient to give the rests the required yielding movement to enable the sole to be in-

clined edgewise, as shown by dotted lines in Fig. 2; but said arms have sufficient resistance to materially aid the operator in keeping the sole in place against the burnishing-face of the tool. The elasticity of the arms also permits the rests to embrace soles of different sizes. I prefer, however, to provide means for varying the normal distance between the rests, to adapt them to different-sized soles, such means consisting in a threaded rod or bolt, H, connecting the inner portions of the arms 11, and provided with jam-nuts J J, adapted to hold the arms 11 at any desired distance apart.

When it is desired to remove the rests from their operative position the arms 11 are turned backwardly on their pivots, as shown in dotted lines in Fig. 1; or, if desired, the arms 11, instead of being pivoted to the arms E E, may be adapted to slide out and in upon said arms E, for the purpose of making the rests operative and inoperative, the arms 11 being provided with elongated slots K, and secured to the arms E by bolts passing through said slots, as seen in the modification shown in Fig. 3, which represents the rests composed of straight pieces without the angles shown in the other figures.

I am aware that two lateral rests arranged to support the opposite edges of a sole have been devised for use in a machine in which the burnishing-tool moves in a curved path conforming to the curvature of the toe of the sole; but such rests are rigid and not capable of lateral separation, automatic or otherwise, nor of

being moved into and out of their operative position. Therefore I do not claim the combination of lateral rests with a reciprocating burnishing-tool, excepting when the rests have the yielding character above described.

Having thus described my invention, I claim—

1. In a sole-edge-burnishing machine having a reciprocating burnishing-tool, the combination, with such tool, of two lateral rests arranged to bear with a yielding pressure upon the opposite edges of a sole when the latter is held in position to present its toe portion to the burnishing-tool, substantially as and for the purpose set forth.

2. The combination, in a sole-edge-burnishing machine, of a reciprocating burnishing-tool, and a pair of lateral rests adapted to be moved into and out of their operative position, as set forth.

3. The combination, with the lateral rests adapted to be secured to a sole-edge-burnishing machine, of an adjustable rod or device for connecting said rests and varying the normal distance between the same, substantially as and for the purpose set forth.

In testimony whereof I have signed my name to this specification, in the presence of two subscribing witnesses, this 31st day of March, A. D. 1881.

WILLIAM GORDON.
